UNITED STATES PATENT OFFICE.

FRANK S. ALIANO, OF NEW YORK, N. Y.

PUNCH-PRESS GUARD.

1,167,611.

Specification of Letters Patent.

Patented Jan. 11, 1916.

Application filed May 6, 1914. Serial No. 836,616.

To all whom it may concern:

Be it known that I, FRANK S. ALIANO, a citizen of the United States, residing in the borough of Brooklyn, city of New York, county of Kings, and State of New York, have invented certain new and useful Improvements in Punch-Press Guards, of which the following is a specification, reference being had therein to the accompanying drawings, which form a part thereof.

My invention relates to punch press guards and more particularly to a type of guard especially adapted for use upon hand fed presses.

15 The guard made the subject matter of my present invention is of a type especially adapted for use with a press in which it is necessary for the pressman to hold the work upon an anvil or die while the ram is descending and until it has completed the work to be done or until the removal of the work from the press. A guard of this type must be so positioned normally as to permit the work to be readily fed upon the anvil and be capable of such actuation prior to or during the descent of the ram as to prevent the hand of the operator remaining between the anvil and the ram while permitting the operator's hand or hands to remain 25 beneath the anvil for the purpose of holding the work thereupon.

30 A guard made in accordance with my invention is adapted, by an oscillatory movement, to be automatically interposed between the surface of the anvil presented toward the ram, and the operator, leaving sufficient clearance below the guard, when set, however, to still permit the operator to hold the work properly in position upon the anvil. The guard will also be returned to normal prior to the succeeding actuation of the press so as to permit the removal of the work from the press and the feeding of another piece of work thereto.

35 I also aim to so mount the oscillatory plate with relation to the press as to permit a quick adjustment of the oscillatory plate with relation to the anvil or the convenient substitution of a plate of one size for 40 that of another.

45 A further feature of the invention is that construction of the plate, by reason of which the operator is forced to insert his hand directly below the portion of the plate intermediate the side edges thereof in order to 50 hold the work in position.

The invention consists primarily in a punch press guard embodying therein an oscillatory guard plate normally projecting downwardly toward the press and above 60 the die and between the ram and the operator and means whereby said guard plate may be swung downwardly and toward the operator to bring the lower edge of said plate upon a plane below the top surface 65 of the die; and in such other novel features of construction and combination of parts as are hereinafter set forth and described and more particularly pointed out in the claims hereto appended.

70 Referring to the drawings: Figure 1 is a side elevation of a punch press showing my guard applied thereto; Fig. 2 is a front view thereof; and Fig. 3 is a detail perspective view of the guard mechanism and a portion 75 of the press adjacent thereto.

Like letters refer to like parts throughout the several views.

In the embodiment of my invention shown in the drawings, *a* indicates the frame of a 80 press; and *b* the fly wheel adapted to be connected with the eccentric shaft *c* by the usual clutch mechanism, not shown. Mounted in vertical guides *d* is the reciprocatory ram *e*. Below the guides *d* and ram *e* is an 85 anvil or die *f* which in the form of press shown, consists of a cylindrical body adapted to receive a can body for the purpose of having the side lap formed thereon. This anvil is supported from the frame *a* in the 90 usual manner.

The type of press described above is old and well-known in the arts and forms no part of my invention. I have illustrated my invention in connection with this type 95 of press because it has particular adaptability thereto. It is to be understood, however, that a guard made in accordance with my invention may be advantageously used on other types of presses, and that I 100 do not intend to restrict myself to the use of the guard upon any particular type of press.

105 The guard mechanism proper, comprises an oscillatory plate *g*, the pivotal supports for which, are arranged above the plane of the top of the anvil or die *f* and upon a vertical plane between the ram *e* and the pressman. Normally, the plate *g* is projected downwardly from its support and 110 away from the operator toward the anvil or die *f*, the angle of such projection being

such as to bring at least a portion of this plate above said anvil or die to an extent to afford that clearance above said anvil or die necessary to permit the can bodies or other articles to be readily fed with relation to the punch and die, and removed after the operation of the press.

That portion of the plate g adjacent the anvil or die f is of a width so that, when said plate is swung toward the operator, the lower edge thereof will extend below the plane of the anvil or die f and thus prevent the hand of the operator remaining between the punch and the anvil or die. At the same time the operator may readily pass his hand below the guard and hold the work upon the anvil or die by grasping it below the point of engagement of the punch with the work.

To prevent the operator passing his hand about either side of the plate g and insert it beneath the ram, I extend said plate laterally thereof well beyond each side of the anvil or die. I also preferably form this plate with the recessed portion g' forming the side extensions g^2-g^3 adapted to project upon opposite sides of the anvil or die f when the guard plate is in its normal position.

In mounting the guard upon a press, I utilize a supporting mechanism which will admit convenient attachment to the frame a and permit the plate to be readily adjusted in its supports, or removed therefrom, to adapt the guard to any particular anvil or die, or different sized presses. I also preferably provide for the adjustment of the plate with relation to its supports. This supporting means comprises the brackets $h'-h'$ secured at opposite sides of the frame a . Carried by the opposite forward ends of said brackets are the vertically adjustable screw studs $i-j$, secured in position in any desired manner as by the lock nuts $i'-j'$.

Carried by each stud $i-j$ is a bearing block k or k' having an opening therethrough adapted to receive said stud, the end of said blocks being slotted as shown to permit it to be firmly clamped upon its stud. By the use of this construction, I am enabled to adjust said blocks vertically upon their studs, or to remove the plate without disturbing the studs or their supporting brackets. This construction also facilitates the installation of the guard.

The blocks $k-k'$ are each provided with a horizontal bearing in which is rotatably mounted a shaft m having a crank arm m' at one end thereof. Carried by said shaft m is a head n preferably of cast metal, having an opening therethrough adapted to inclose the shaft m and a split top n' by means of which the head may be adjusted with relation to the anvil or die and clamped upon said shaft by means of clamp screws n^2 as

shown. The plate g is mounted upon said head n by means of the bolts n^3 , said plate being provided with a plurality of spaced bolt holes g^3 to facilitate the adjustment of the plate with relation to said head. One side of the head is made flat so as to permit this adjustment of the plate thereon.

Mounted upon a stud upon the frame a , is a bell crank lever one arm o of which is connected to the crank arm m' by the link p ; and the other arm o' of which is connected by the link q with the clutch mechanism controlling the operation of the ram e and also by the link r with the foot pedal s or other means for controlling said clutch mechanism. By this construction the operation of the guard may be accurately timed with relation to that of the ram. By using a lost motion connection between the arm o' and the link q the guard may be set before the clutch is tripped. In the form of the invention shown, the spring s' acting upon the pedal s may be utilized for restoring the plate g to normal after each actuation of the press, although, if desired, other means for restoring said plate to normal may be used without departing from the spirit and scope of the invention.

The operation of the herein described device is as follows: When the press is at rest the oscillatory guard plate g will be in the position shown in Fig. 1, the side extensions $g'-g^2$ thereof, extending upon opposite sides of the anvil or die e and the recess intermediate said extensions positioned above the die or above the normal plane of the die. With the guard in this position a can body or other piece of work may be readily fed upon the anvil or die and between it and the guard plate. When the work is in place the operator depresses the pedal s against the tension of its spring s' , thus rocking the bell crank lever o' and through the links $p-q$, successively imparting oscillatory movement of the plate g and tripping the clutch controlling the ram e . As the plate g is oscillated it will swing downwardly and toward the operator until the lower edge thereof intermediate the extension $g'-g^2$ will come to position in a below the top surface of the anvil or die, thus effectively guarding the space above said anvil or die. The extensions $g'-g^2$ will serve to effectively prevent the operator inserting his hand beneath the guard and upwardly at one side of the anvil or die. While the plate g will effectively protect the space between the anvil or die and the ram, it will still permit the hand of the operator to be inserted below that portion of the plate adjacent the anvil or die for the purpose of holding the work upon said anvil or die until the lap or other work is applied and it is necessary to remove the work.

If it be desired to adjust the plate g , such

adjustment may be secured by releasing the clamping blocks *k*—*k'* and raising and lowering them upon the studs *i*—*j*. If desired, the studs *i*—*j* may be adjusted, the said blocks being released to permit the free adjustment of said studs and avoid rotary movement of said blocks.

By the use of the studs *i*—*j* and blocks *k*—*k'* the guard may be readily and conveniently applied to a press and it may be quickly adjusted.

Upon the reversal of the movement of the ram, the clutch mechanism, bell crank lever *o*—*o'* and pedal *s* will be restored to normal, thus carrying the guard plate *g* to its normal position and affording that clearance necessary to permit the removal of the work from the press.

It is not my intention to limit the invention to the precise details of construction shown in the drawings, it being apparent that such may be varied without departing from the spirit and scope of my invention.

Having described my invention what I claim as new and desire to have protected by Letters Patent is:—

1. A punch press guard embodying therein an oscillatory guard plate normally projecting downwardly toward the press and above the anvil or die and between the ram and the operator, manually operative means whereby the movement of the ram of a press is controlled and operative connections between said means and said oscillatory guard plate whereby said guard plate may be swung downwardly and toward the operator to bring the lower edge of said plate upon a plane below the top surface of the anvil or die.

40 2. A punch press guard embodying therein an oscillatory shaft and guard mounted thereon and movable therewith, said plate normally projecting downwardly toward the press and above the anvil or die and between the ram and the operator, a bell crank lever, a plurality of links whereby one arm of said lever may be connected to the controlling pedal and the clutch mechanism, a crank arm carried by said oscillatory shaft and a link connection between the other arm of said bell crank lever and said crank arm whereby the depression of the pedal to said clutch will swing said plate downwardly and toward the operator to bring the lower edge thereof upon a plane below the top surface of the anvil or die.

3. A punch press guard embodying therein an oscillatory guard plate normally projecting downwardly toward the press and above the anvil or die and between the ram and the operator, said plate having thereon extensions disposed to the opposite sides thereof and adapted to straddle the anvil or die whereby the work may be held

upon said anvil or die beneath said plate but access to said anvil or die about the sides of said plate is prevented.

4. A punch press guard embodying therein a plurality of brackets adapted to be disposed upon opposite sides of a press, 70 studs carried by each of said brackets a bearing block adapted to be mounted upon each of said studs, means whereby each of said blocks may be clamped upon its stud, an oscillatory shaft the opposite ends of which are mounted in said blocks respectively, a guard plate mounted upon and movable with said shaft, said plate normally projecting downwardly toward the press and above the anvil or die and between the ram and the operator and means whereby said guard plate may be swung downwardly and toward the operator to bring the lower edge of said plate upon a plane below the top surface of the die.

5. A punch press guard embodying therein a plurality of brackets adapted to be disposed upon opposite sides of a press, screw studs mounted in said brackets respectively, means whereby each of said blocks may be clamped upon its stud, an oscillatory shaft the opposite ends of which are mounted in said blocks respectively, a guard plate mounted upon and movable with said shaft, said plate normally projecting downwardly toward the press and above the anvil or die and between the ram and the operator and means whereby said guard plate may be swung downwardly and toward the operator to bring the lower edge of said plate upon a plane below the top surface of the die.

6. A punch press guard embodying therein an oscillatory guard plate normally projecting downwardly toward the press and above the die and between the ram and the operator, supporting means for said plate whereby the angle or projection of said plate may be adjusted, manually operative means whereby the movement of the ram of a press is controlled and operative connections between said means and said oscillatory guard plate whereby said guard plate may be swung downwardly and toward the operator to bring the lower edge of said plate upon a plane below the top surface of the anvil or die.

7. A punch press guard embodying therein an oscillatory shaft, a head clamp thereon, a guard plate carried by said head, 120 said plate normally projecting downwardly toward the press and above the die and between the ram and the operator, manually operative means whereby the movement of the ram of a press is controlled and operative connections between said means and said oscillatory guard plate whereby said guard plate may be swung downwardly and

toward the operator to bring the lower edge of said plate upon a plane below the top surface of the anvil or die.

8. A punch press guard embodying therein an oscillatory shaft, a head clamp thereon, a guard plate carried by said head, said plate normally projecting downwardly toward the press and above the anvil or die and between the ram and the operator, an

operative connection between said plate and 10 said head whereby said plate may be adjusted radially of said shaft.

In witness whereof I hereunto affix my signature this 1st day of May, 1914.

FRANK S. ALIANO.
